YARN TWISTER

Albert E. Winslow, Mystic, Conn., assignor, by
mesne assignments, to Farrel-Birmingham
Company, Incorporated, Ansonia, Conn., a cor-
poration of Connecticut

Application September 11, 1943, Serial No. 501,963

2 Claims. (Cl. 57—66)

This invention relates to a yarn-handling machine, more particularly to the ring twister type.

In machines of this character it is usual to take by feed rolls from a supply package a single or two parallel yarns and in the latter case deliver the yarns separately to packaging spindles where they are individually twisted. The feed rolls grip the yarn and pull the same and require of the yarn that it be of sufficient strength to withstand such treatment. In certain tender yarns this treatment is abusive of the yarn and in such yarns as glass yarns certain of the fibers are broken which is detrimental to the yarn.

One of the objects of this invention is to reduce contact with the yarn which may cause it to break.

Another object is to twist the yarn back to the supply package to bind in all loose ends and strengthen the yarn as it is initially supplied and when parallel yarns are used to assist in their separation.

Another object of this invention is to drive the supply package having the two parallel yarns wound thereon so as to eliminate necessity of gripping or nipping feed rolls for drawing the yarn from the supply package, thus making it unnecessary to engage the yarns between the supply package and the delivery package except for a light guiding engagement which may occur on the yarn.

Another object of the invention is to permit the twist which is applied to the yarn traveling from the ring traveler back to the supply package over a substantial distance during which distance the twist is placed in the yarn.

Another object of the invention is to provide a supply package which may be easily mounted upon and withdrawn from the machine even though this supply package is driven.

Another object of this invention is to provide a means for varying the drive of the supply package so as to accommodate the supply of the package to the speed of the spindle to which it is being delivered.

Another object of the invention is to provide an arrangement in which the unit consisting of a supply package and a pair of spindles may be arranged side by side along a length of machine with a common drive for all of the supply packages and a common drive for the spindles.

Another object of the invention is to provide an arrangement so that the same frame may be equipped with a plurality of side by side units in back to back relation with a spindle drive for each back to back units of the assembly.

With these and other objects in view, the invention consists of certain novel features of construction, as will be more fully described and particularly pointed out in the appended claims.

In the accompanying drawing:

Fig. 1 is a sectional view through the twister frame between the delivery packages of Fig. 2 showing the yarn as guided from the supply package to the spindle package which is surrounded by the ring and traveler:

Fig. 2 is a fragmental front elevation of a modification largely diagrammatic and illustrating the yarn as led from the supply package to two spindles.

In proceeding with this invention I drive the supply package of yarn so as to cause the same to feed the yarn supply and then take up the yarn on a bobbin mounted on the spindle and surrounded by the ring and traveler so that twist is placed in the yarn running from the delivery package back to the supply package without any intermediate feed rolls whereby to materially strengthen the yarn and bind in all the short ends and also assist in separation when parallel 25 yarns are used. The yarn which is dealt with in a machine of this character is very fine yarn sometimes running ninety thousand yards to the pound.

With reference to the drawing 10 designates 30 generally the structural framework having a supporting stand 11 and horizontal angle bars 12 from which brackets 13 extend for guiding the thread guide rod 14 carrying the thread guide 15 at the upper end thereof and which has the ring rail 16 and ring 17 carried thereon for reciprocating motion along the spindle package designated generally 18 and mounted on the spindle blade. The spindle also includes a whirl 19 which is driven from the belt 20 which travels in a vertical plane and runs lengthwise of the machine to operate all of the spindles or take-up packages throughout the length of the machine. The spindle is suitably mounted in a swinging bracket which is urged against the belt for driving the same and may be withdrawn from the belt for stopping the spindle, all as more particularly pointed out in my co-pending application Ser. No. 508,817 now Patent No. 2,375,805, dated May 3, 1945, which relates to a stop motion and mechanism for withdrawing the spindle from operating position.

At the upper end of the supporting stand a shaft 21 is rotatably mounted in a bearing 22 carrying a mandrel at one end for the mounting 55 of a supply package 23 thereon. This shaft also

carries a drum 28 with which the back of the V belt 29 may engage to drive the same. A V-pulley 30 grooved at 31 fits this belt and serves to move it into engagement with the drum 28 so that the back of the belt may drive the drum.

The yarn on the package 21 is led from this package through the pigtail guide 32 and thence to the bobbin 18. By reason of the ring 17 and traveler 33 the yarn is caused to balloon and twist with the twist traveling back to the supply package 27 by reason of the substantially straight path of the yarn. The guide 36 only lightly touches it. By the twist traveling back to the supply package all of the ends of the yarn are bound in together making a strong strand and one which cannot pull apart from a point close to the supply package. This is exceedingly important in handling small diameter yarn, such as glass yarn which may run ninety thousand yards to the pound. Also by delivering directly from the supply package to the take-up package without any intermediate feed rolls less handling of the yarn is required which also in small brittle yarn as glass serves to abuse the yarn to a substantial extent. Thus it is additionally advantageous to cause the yarn to travel from the supply package to the take-up package merely over a minimum number of guiding bars which do not materially deflect it from a straight path.

In some cases in the making of yarn of this character it is advantageous from the standpoint of previous processing to wind more than one yarn end on a package in which case a saving is effected by running two yarn ends or more in parallel relation upon a package, such as a supply package 27. In taking such parallel yarns from the supply package one yarn end will be directed to one spindle while the next yarn end will be directed to the next spindle, and so on if there are more than two. And in Fig. 2 I have illustrated one yarn end 35 as heretofore described as a single, while the parallel yarn 35' is directed over to the package 18' where it travels through the traveler 33' moving about ring rail 17' to be assembled upon the package 18' similarly. In this case the

yarn extends over a guide 36' and through the guide 32' and the twist also runs back to the guide 36' over which the second yarn 35' extends. The twist in the companion yarn 35 will as previously described run back to the supply package and will assist in separating the two yarns from each other. It will be understood that the supply packages are driven in each case and the yarn is led with a twist therein running from the take-up package back to the supply package.

The supply packages are usually rather small and it is unnecessary to equip the driving belt 29 with a variable drive to compensate for the decreasing diameter of the package although if larger yarn packages were supplied this expedient would be adopted in order that the delivery might be more uniform and the yarn more uniform throughout the extent of its length in which case a "Reeves" drive with V belt may be used.

I claim:

1. In a yarn handling machine, a unit assembly comprising a supply package of a plurality of parallel strands, an individual spindle for each of said strands, guides for directing one strand to each spindle, one strand leading straight enough to carry the twist back to the supply package, means for driving the spindles to take up and twist each strand and co-related means for driving said supply package constituting the only means for transferring the strands from the supply package to the spindle packages.

2. In a yarn handling machine, a unit assembly comprising a supply package of a plurality of parallel strands, an individual spindle for each of said strands, guides for directing one strand to each spindle, one strand leading straight enough to carry the twist back to the supply package, means for driving the spindles to take up and twist each strand and co-related means for driving said supply package, said strands being free from contact with other feeding means whereby said twist extends back to the supply package.

ALBERT E. WINSLOW.
